COPYING MACHINE

William G. Delp, Pasadena, and Robert J. Elder, Sierra Madre, Calif., assignors to Royal Industries, Inc., Pasadena, Calif., a corporation of California

Filed May 20, 1966, Ser. No. 2,373

Term of patent 14 years

(Cl. D61—1)

FIG. 1 is a right hand perspective view of a copying machine showing our new design; and

FIG. 2 is a right hand perspective view, illustrating the copying machine of FIG. 1 in an inverted position.

The side of the copying machine opposite to the right hand side illustrated in FIG. 1 is identical to that illustrated.

FIG. 1 is shaded to indicate contrast in appearance, while the front face is lined to indicate a screened grille.

We claim:

The ornamental design for a copying machine, as shown and described.
